F. W. WALTZ.

GAS JET.

APPLICATION FILED MAR. 22, 1912.

Patented July 1, 1913.

UNITED STATES PATENT OFFICE.

FREDERICK W. WALTZ, OF ALLENTEWON, PENNSYLVANIA.

GAS-JET.

1,066,349.

Specification of Letters Patent.

Patented July 1, 1913.

Application filed March 22, 1912. Serial No. 685,437.

To all whom it may concern:

Be it known that I, FREDERICK W. WALTZ, citizen of the United States, residing at Allentown, in the county of Lehigh and State of Pennsylvania, have invented new and useful Improvements in Gas-Jets, of which the following is a specification.

This invention relates to gas jet attachments and more particularly to attachments for wall brackets.

The principal object of the invention is to provide a simple, efficient and cheaply constructed device of this character which may be conveniently and readily applied to an ordinary wall bracket so as to prevent the jet arm from being thrown into such a position that the flame would be held in dangerous proximity to the wall.

Further objects of this invention will appear as the following specific description is read in connection with the accompanying drawing, which forms a part of this application, and in which:

Figure 1 is a side view. Fig. 2 is a top plan view. Fig. 3 is a section through the bracket showing the attachment in rear elevation.

Referring more particularly to the drawing, 1 represents a supporting wall and projecting therefrom is the ordinary gas bracket 2 upon which is pivotally connected the jet arm 3. The attachment comprises a single strand of wire bent at its ends laterally, as shown at 4, and then into depending loops 5 which are flared at their lower ends, as shown at 6, so as to conveniently engage over the bracket 2. Beyond the loops, the wire is bent so that its separate portions diverge as shown at 7 in Fig. 2. At the end of the diverging portion of the wire, the separate parts are upwardly bent, as shown at 8, an equal distance to the thickness or depth of the arm 3 and are then bent rearwardly on converging lines, as shown at 9, so as to surround the upper end of the pivot screw 10. The converging portions are integrally connected together in any suitable manner or the apex of the convergence may be the middle portion of the

wire and the terminals thereof may lie 50 across the bracket 2 unconnected. The loops 5 constitute bracket engaging fingers which serve to hold the device upon the bracket and the upwardly extending portions 55 8 constitute limiting stops which limit the movement of the arm 3 and prevent it from being swung around so that the blaze from the gas tip would be in dangerous proximity to the wall.

It will be clearly understood that while 60 this device has been illustrated in its simplest form, many modifications may be resorted to in practice without departing from the spirit or scope of the invention. For instance, the entire structure may be 65 stamped out of sheet metal and pressed into shape if found to be more desirable in practice.

What I claim as new is:

1. An attachment for wall gas brackets 70 comprising a single strand of wire having engaging fingers bent up therefrom and adapted to straddle the bracket, and diverging stop members connected together and forming a continuation of the fingers and 75 adapted to limit the movement of the jet arm.

2. An attachment for gas wall brackets comprising bracket clamping arms, and diverging fingers secured thereto for limiting 80 the movement of the jet arm.

3. An attachment for gas wall brackets comprising bracket clamping means, and diverging fingers secured thereto for limiting 85 the movement of the jet arm in either direction.

4. An article of manufacture, an attachment for gas wall brackets comprising means secured to the bracket and extended into the path of the jet arm to limit the 90 movement thereof.

In testimony whereof I affix my signature in presence of two witnesses.

FREDERICK W. WALTZ.
